REFRIGERATED BEVERAGE DISPENSING MACHINE OR SIMILAR ARTICLE

Clark Lofgren, Golden Valley, Minn., assignor to The Cornelius Company, Anoka, Minn., a corporation of Minnesota

Filed Dec. 3, 1968, Ser. No. 14,763

Term of patent 14 years

Int. Cl. D15—12

U.S. Cl. D94—3

FIG. 1 is a perspective view showing the front and one side of a refrigerated beverage dispensing machine showing my new design, the other side having a similar appearance.

FIG. 2 is a rear view thereof.

FIG. 3 is a top view thereof.

I claim:

The ornamental design for a refrigerated beverage dispensing machine or similar article, substantially as shown and described.
